(57) **CLAIM**

I claim the ornamental design for a closure, as shown and described.

DESCRIPTION

FIG. 1 is a front perspective view of a closure, showing my new design;

FIG. 2 is a bottom perspective view thereof;

FIG. 3 is a front view thereof, the right, back, and left view being a mirror image thereof;

FIG. 4 is a top view thereof; and,

FIG. 5 is a bottom view thereof.

The ornamental design which is claimed is shown in solid lines in the drawings. The broken lines are shown for the purpose of illustrating parts of the article that form no part of the claimed design.

1 Claim, 5 Drawing Sheets
